UNITED STATES PATENT OFFICE.

JOHN C. BLOOM, OF KALAMAZOO, MICHIGAN, ASSIGNOR TO HIRAM B. MILLER, OF SAME PLACE.

DRIVE-CHAIN.

SPECIFICATION forming part of Letters Patent No. 293,407, dated February 12, 1884.

Application filed September 28, 1881. (Model.)

To all whom it may concern:

Be it known that I, JOHN C. BLOOM, a citizen of the United States, residing at Kalamazoo, county of Kalamazoo, State of Michigan, have invented a new and useful Chain-Belt, of which the following is a specification.

My invention relates to that class of chain-belts the links of which are provided with open coupling-hooks formed integral therewith, and has for its object certain improvements to facilitate their utility and operation.

In the drawings forming a part of this specification, in which similar letters of reference indicate like parts, Figure 1 is a side view of a section of my improved belt; Fig. 2, top view of same; Fig. 3, side view of link, having the coupling-bar made the other side up, and Fig. 4 detached portions of Fig. 1.

The links of the chain are constructed with the side bars connected by a cylindrical coupling-bar, D, at one end, and an open-hook, c, at the other end, adapted to receive the coupling-bar D and form cylindrical bearings therefor, said hook being just sufficiently large to receive said coupling-bar. At one end of the side bars are formed convex shoulders e e and at the other end concave shoulders t t, the convexity of one conforming to the concavity of the other, and all having a like radius. I form the portion n, Fig. 1, on a flat oblique angle, and the shoulders S S below the concave shoulders t t on a like angle in line with portion n, to facilitate the coupling and fix the angle of the links while coupling and uncoupling.

In the operation, referring to Figs. 1 and 2, it will be seen that all the slack of the chain needed to admit of its being coupled and uncoupled corresponds to the diametrical distance through the cylindrical coupling-bar D, 40 and that, when the links are carried to a used position, said coupling-bar D just fills the circular hook, and the convex shoulders e e exactly fit into and bear against the concave shoulders t t.

Such a construction of chain-belt is strong, conveniently operated, and a very tight tension can be had on the sprocket-pulleys, as the coupling-bar is not forced away from the body of the contiguous link in bringing the links to 50 a used position. With the modification shown in Fig. 3 the chain may be conveniently used the other side out.

Having thus described my invention, what I claim is—

A chain-belt consisting of links composed of side bars having concave shoulders at one end, and convex shoulders at the other end, the former shoulders adapted to fit into and bear against the latter, and all having a like radius, 60 said side bars being connected by a cylindrical coupling-bar at one end and by a hook at the other end, forming a cylindrical bearing adapted to receive said coupling-bar, all substantially as set forth.

JOHN C. BLOOM.
